UNITED STATES PATENT OFFICE.

JOSEPH STEWART SMITH, JR., OF NEW YORK, N. Y.

VEHICLE TOP-BOW HOLDER.

1,120,418.

Specification of Letters Patent.

Patented Dec. 8, 1914.

Application filed November 14, 1913. Serial No. 801,068.

To all whom it may concern:

Be it known that I, JOSEPH STEWART SMITH, Jr., a citizen of the United States of America, residing at New York, in the county of New York and State of New York, have invented certain new and useful Improvements in Vehicle Top-Bow Holders, of which the following is a specification, reference being had therein to the accompanying drawings.

This invention relates to a vehicle top bow holder especially designed for vehicle tops and canopies which, by reason of pivotally connected side bows, the top or canopy is adapted, when out of use, to be folded. As well known, the bows rest upon each other and are subjected to jolting, frictional contact and chafing, with the result that the bows are scarred, injured and often broken, especially the pivotal connections between the bows.

My invention aims to provide a novel holder that can be easily and quickly installed to separately support the weight of each bow in a manner, as hereinafter set forth, that prevents frictional contact, rattling, injury to the vehicle top, and breakage of the bows or their appurtenant parts.

The mechanical construction by which I accomplished the above and other objects will be hereinafter specifically described and then claimed, and reference will now be had to the drawing, wherein there is illustrated a preferred embodiment of my invention, but it is to be understood that the structural elements are susceptible to such variations and modifications as fall within the scope of the appended claims.

In the drawings, Figure 1 is a side elevation of the holder in a closed position; Fig. 2 is a horizontal sectional view of the same; Fig. 3 is a detail perspective view of the upper end of the holder showing the same in an open position; and Fig. 4 is a plan of the holder in a closed position.

A holder in accordance with this invention comprises a channel-shaped stock 1 having the upper and lower ends thereof cut away to provide sets of apertured ears 2 and 3. The ears 2 are connected by a transverse rivet 4 and the ears 3 by a transverse rivet 5. Pivotally mounted upon the rivet 5 between the ears 3 is the barrel 6 of a clamping arm, said arm comprising a strip of metal approximately the same length as the stock 1, said strip of metal being bent to provide

curved ends and intermediate fingers or bow-lifts 8. The fingers 8 are equally spaced and coöperate with the stock 1 in providing a plurality of separated pockets 9 for bows 10. That portion of the metallic strip 7 forming the back of each pocket is reinforced by a stiffening bar 11 riveted or otherwise connected to the strip of metal 7, as at 12. The bar 11 is preferably channel-shaped whereby the side flanges thereof will engage the edges of the strip of metal 7 and the ends of the stiffening bar 11 are slightly bent to conform to the curvature of the ends of the strip of metal.

The upper end of the strip of metal 7 terminates in a latch 13 having a tongue 14 adapted to extend between the apertured ears 2, beneath the rivet 4, when the arm is in a closed position relatively to the stock 1. The tongue 14 is of a less width than the latch 13 and the side edges of said latch, adjacent to the inner end of the tongue 14, are cut or sheared, as at 15 and the cut or sheared material bent upwardly to provide parallel vertical lugs 16. The formation of the lugs 16 provides oppositely disposed lateral extensions 17 that present shoulders adapted to engage the edges of the ears 2 and limit the closing movement of the arm or the inward movement of the tongue 14 between the ears 2. To retain the arm in a closed position a keeper is pivotally mounted upon the rivet 4. The keeper comprises a compound curve 18 having the side edges thereof cut away to provide shoulders 19, and a portion of the sheared material is bent upwardly to form parallel apertured ears 20 that are pivotally mounted upon the rivet 4 at the upper end of the stock. The shoulders 19 are adapted to engage behind the vertical lugs 16 and retain the shoulders of the lateral extension 17 in engagement with the upper end of the stock 1. To retain the keeper 18 in a closed position, the latch 13 is cut or punched, as at 21 and the punched material bent upwardly to provide a resilient curved locking member 22 adapted to extend through an opening 23 provided therefor in the keeper 18. The member 22 engages a wall of the opening 23 and the resiliency and curvature of said member is sufficient to hold the keeper in a closed position. The shape of the member also permits of the keeper 18 being snapped into and out of engagement with said member.

To prevent the bows 10 from being

marred or injured by the metallic surfaces of the stock 1 and the pivoted arm 1 use a cushioning member 24 preferably in the form of a strip of braided fabric. One end 5 of the strip is riveted or otherwise connected, as at 25 to the upper inner face of the stock 1, said strip of fabric extending downwardly and riveted or otherwise connected, as at 26 to the inner side of the lower curved 10 end of the pivoted arm, whereby said strip of fabric is retained in engagement with the inner face of the stock 1. The strip of fabric then extends upwardly to line the inner side of the metallic strip 7, that is, the 15 fingers 8 and the pockets 9 thereof. The strip of fabric is retained in position by the same rivets or fastening means 12 employed for retaining the stiffening bar 11 in engagement with the strip of metal 7. The 20 end of the strip of fabric is riveted or otherwise connected, as at 27 to the latch 13, between the vertically extending lugs 16 thereof.

Arranged in the stock 1, intermediate the 25 ends thereof, is a channel-shaped member 28, which adds rigidity and strength to the stock 1, whereby a socket member 29 can be riveted or otherwise connected to the stock 1 without impairing the supporting 30 stand of said stock. The socket member 29 is adapted to receive a supporting iron extending from a vehicle body, whereby the holder will be correctly positioned to receive the bows of a collapsed or folded vehicle top or canopy.

From the fore-going it will be observed that my invention possesses the following characteristics and advantages:—First, that of having a clamping arm when in an open 40 position permits the bows 10 to readily enter between the arm and stock, and when closed the bows are separately and firmly held in the pockets 9 and prevented from contacting. Second, that the closing movement 45 of the clamping arm is limited and consequently un-due pressure cannot be brought to bear upon the bows or the cushioning member of the holder unduly worn or compressed. Third, that of relieving the locking 50 member of the latch 13 from stresses and strains when the keeper 18 is in a closed position. This is accomplished by the shoulders 19 of the keeper 18 engaging behind the vertical lugs 16, and it is to this detail of con-

struction that I attach considerable importance, as a clamping arm is prevented from accidentally swinging to an open position. Fourth, that of making the holder of sheet metal pressed, stamped or otherwise shaped to desired form, thereby obviating the necessity of using castings which are susceptible to fracture and other injuries. With the parts of the holder made of sheet metal can be easily finished to harmonize with the vehicle body in connection with which the 60 holder is used. Fifth, that the elements 13 to 22 inclusive constitute a novel hold-fast device or a connection for two members and as such can be used in connection with various articles.

What I claim is:—

1. A vehicle top bow holder, comprising a sheet metal channel-shaped stock, a sheet metal clamping arm pivotally connected thereto and shaped to coöperate with said stock in providing pockets adapted to receive and separately support the bows of the vehicle top, means secured longitudinally of said arm to add rigidity thereto, a single cushion member attached to said stock and to said arm and adapted to cushion bows supported between said stock and said arm, said member being attached to said arm by the same securing means as the rigid means of said arm; and means including a latch carried by said stock and adapted to be snapped into engagement with said arm to bind the upper end of said arm against said stock in a closed position.

2. In a vehicle top bow holder, a stock, 90 a clamping arm pivotally connected thereto and shaped to coöperate with said stock in separately supporting the bows of a vehicle top, lugs carried by said arm, a shoulered keeper carried by said stock and 95 adapted to be snapped into engagement with the lugs of said arm to retain said lugs between said stock and the shoulders of said keeper and said arm in a closed position, and means carried by said arm adapted to 100 retain said keeper in a closed position upon said arm.

In testimony whereof I affix my signature in presence of two witnesses.

JOSEPH STEWART SMITH, JR.
